(57) **CLAIM**

The ornamental design for a wheel for forklift truck, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of a wheel for forklift truck of the present invention;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front perspective view thereof;

FIG. 8 is a rear perspective view thereof; and,

FIG. 9 is a cross-sectional view thereof, taken along the line 9-9 of FIG. 1.

The portions of the drawings that are shown de-emphasized as faded out and bound by broken lines, depict portions of the wheel for a forklift that form no part of the claimed design.
